FLUID CONCENTRATION MONITOR FOR AN ARTIFICIAL KIDNEY MACHINE

Charles P. Johnson, Seal Beach, Calif., assignor to Western Gear Corporation, Lynwood, Calif., a corporation of Washington

Filed Apr. 21, 1969, Ser. No. 16,838

Term of patent 14 years

Int. Cl. D24—02

U.S. Cl. D83—1

FIG. 1 is a perspective view of a fluid concentration monitor for an artificial kidney machine embodying my new design;

FIG. 2 is a rear elevational view of the fluid concentration monitor shown in FIG. 1;

FIG. 3 is a bottom plan view of the fluid concentration monitor shown in FIG. 2; and

FIG. 4 is a left side elevational view of the fluid concentration monitor shown in FIG. 1.

I claim:

The ornamental design for a fluid concentration monitor for an artificial kidney machine, as shown.
